CLAIM

The ornamental design for an automobile and/or toy replica thereof, as shown and described.

DESCRIPTION

FIG. 1 is a front perspective view of an automobile and/or toy replica thereof showing our new design;

FIG. 2 is a rear perspective view thereof;

FIG. 3 is a front view thereof;

FIG. 4 is a rear view thereof;

FIG. 5 is a top plan view thereof; and,

FIG. 6 is a right side view thereof; the left side view being a mirror image thereof.

The ghosted or low contrasted showing of the automobile and/or toy replica thereof is provided for the purposes of illustrating portions of the automobile that form no part of the claimed design.

1 Claim, 6 Drawing Sheets
